US0D1068058S

(12) **United States Design Patent** (10) **Patent No.:** **US D1,068,058 S**
(45) **Date of Patent:** **** Mar. 25, 2025**

(54) **IMPELLER**

(71) Applicant: **Foshan Samyoo Electronic Co., Ltd.,**
Guangdong (CN)

(72) Inventor: **Shengcheng Lu**, Guangdong (CN)

(73) Assignee: **FOSHAN SAMYOO ELECTRONIC
CO., LTD.**, Foshan (CN)

(**) Term: **15 Years**

(21) Appl. No.: **29/864,356**

(22) Filed: **May 23, 2022**

(30) **Foreign Application Priority Data**

Apr. 27, 2022 (CN) 202230244889.3

(57) **CLAIM**

The ornamental design for an impeller, as shown and described.

DESCRIPTION

FIG. 1 is a front elevation view of an impeller showing my design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a perspective view thereof;

FIG. 8 is another perspective view thereof; and,

FIG. 9 is a cross-sectional view along line 9-9 in FIG. 6. The portion shown in broken lines is for illustrative purposes only and forms no part of the claimed design.

1 Claim, 7 Drawing Sheets
